UNITED STATES PATENT OFFICE.

LOUIS A. MAXSON, OF CLAREMONT, NEW HAMPSHIRE, ASSIGNOR TO SULLIVAN MACHINERY COMPANY, A CORPORATION OF MASSACHUSETTS.

COMPRESSOR.

Application filed October 8, 1921, Serial No. 506,384. Renewed September 6, 1924.

To all whom it may concern:

Be it known that I, LOUIS A. MAXSON, a citizen of the United States, residing at Claremont, in the county of Sullivan and 5 State of New Hampshire, have invented certain new and useful Improvements in Compressors, of which the following is a full, clear, and exact specification.

My invention relates to compressors and 10 more especially to unloading systems for compressors.

It has for its object to provide an improved mechanism cooperating with the compressor in a new and improved manner 15 whereby the same may be automatically unloaded or loaded as conditions vary. A more specific object of my invention is to provide improved controlling mechanism especially adapted to multi-stage compressors wherein one set of inlet valves, as for instance, those of the low pressure cylinder, are actuated to unload the compressor and wherein another set of inlet valves as for instance those of the high pressure cylinder, 20 are subsequently actuated to complete the unloading of the compressor, these last mentioned valves being controlled by improved means automatically responsive to the variations in pressure resulting from unloading the low pressure cylinder. A further 25 object of my invention is to provide an improved type of unloading mechanism adapted to cooperate with either the valves of the high or low pressure cylinders and by reason of its particular construction automatically producing the desired delay between 30 the unloading of the respective cylinders. These and other objects of my invention will, however, hereinafter more fully appear. 35

In the accompanying drawings I have shown for purposes of illustration my invention as applied to a two-stage compressor, although it will be readily understood that the same is not limited to a machine of 40 the particular construction shown.

In these drawings,—

Fig. 1 is a partial side elevation of the compressor equipped with the illustrative form of my improvement.

50 Fig. 2 is a partial side elevation of a com-

pressor provided as to one stage thereof with my improved type of inlet valve actuating mechanism hereinafter described, the compressor, however, being unloaded as to the low pressure cylinder by intake closing 55 means.

Fig. 3 is a central vertical section on an enlarged scale through a fragmentary portion of the intake chamber and one head of a compressor cylinder showing my improved 60 mechanism in position.

In this illustrative construction I have shown a compressor 1 mounted upon a suitable base 2 and having low and high pressure cylinders 3 and 4 in which are movable pistons (not shown) in a well-known manner, the operating means for these pistons not being illustrated as the construction is well known in the art. Connecting the cylinders 3 and 4 is an intercooler 5 and a pipe 6 leads 65 from the discharge chest of the high pressure cylinder 4 to a receiver 7. For the purpose of unloading the compressor, I employ an unloading system resembling in some features that disclosed in the application of one 70 Fred D. Holdsworth, Serial No. 134,452, filed November 28, 1916, and comprising a connection 8 leading to a pilot valve 9, herein of the well known Judson type illustrated 75 in Patent No. 1,141,975, granted to one John 80 L. Osborne on June 8, 1915. The pilot valve 9 controls the supply of air through the pipe 8 from the receiver to branch passages 10 and 11 which lead to T's 12 and 13, respectively, and from these T's air admitted 85 through the pilot valves is led to means cooperating with the inlet valves of the high and low pressure cylinders respectively, and generally designated 14, these means constituting per se and in combination 90 with the remainder of the structure disclosed, my invention.

Considering the form of the same shown in Fig. 3 it will be noted that the cylinder shown therein is provided with the usual inlet valve 15 having a stem 16 connected thereto and provided with a collar 17 arranged at the opposite end of the stem, which collar is engaged by a spring 18 abutting against a flange 19 formed on the 95 100

stem guide 20 in the valve cage member 21. The construction as so far described is of familiar construction. Cooperating with this mechanism is an improved mechanism 5 comprising a housing 22 having herein cylinders of differential bores 23 and 24, respectively, formed herein in alinement and communicating with each other. Within the cylinders 23 and 24 is reciprocable a compound piston comprising a large head 25 fitting the larger cylinder 23 and a small head 26 fitting the smaller bore 24. The compound piston is provided with a stem 28 adapted to engage the collar 17 or the end of 10 the stem 16 and, upon upward movement of the pistons, unseat the inlet valves and maintain them unseated. It will be noted that the upper surface of the larger piston 25 is exposed to the pressure in the intake 15 chamber of the cylinder to which it is attached and accordingly that dependent upon the pressure existing in the intake chamber, upon the relative areas of the pistons 25 and 26, and upon the pressure acting upon the 20 end of the smaller piston 26, the delay in operation between the moment of admission of pressure beneath the piston 26 and the upward movement of the compound piston will be variable. It will be clear that this 25 mechanism can be connected to the low pressure cylinders and that due to the fact that the pressure in the intake is atmospheric pressure only, as soon as the pilot valve 9 operates, the compound pistons will be 30 moved upward and unload the low pressure cylinder by opening the inlet valves thereof. In the case of the high pressure cylinder, however, the pressure which is admitted 35 through the branch pipe 10 simultaneously 40 with the admission of pressure through the pipe 11 to the low pressure unloading mechanism, will not be able to raise the pistons and open the inlet valves due to the fact that intercooler pressure may be in the 45 case of the compound compressor, say fifty pounds, and this pressure acting upon the piston 25, upon an area, for example, ten times that of the area exposed to receiver pressure will easily keep the high pressure 50 cylinder loaded and actively pumping down intercooler pressure until that pressure has been pumped down to say ten pounds if receiver pressure is slightly above one hundred pounds. It will thus be evident that a 55 considerable delay will be inserted between the respective unloadings of the high and low pressure cylinders and that a single mechanism identical in construction may be employed with the inlet valves of the respective cylinders and will automatically by reason of its construction and cooperation 60 with the inherent peculiarities of the phenomena in the intake chambers of the several cylinders, operate in the desired man-

ner. It will be observed that the parts 23, 65 24, 25, 26, etc., constitute valve controlling servo-motors.

It will be clear that instead of the mechanism as shown in Fig. 1, a mechanism of the intake closure type could be employed 70 upon the low pressure cylinder as shown in Fig. 2 of the accompanying drawings and the cooperation of my improved mechanism with the high pressure cylinder would be the same in either case. It will also be 75 understood that in practice the pistons 25 and 26 will be packed with cup leathers or otherwise arranged to prevent leakage and that the relative areas of the pistons will be 80 varied to suit the conditions and results desired, even being made the same in some cases and with some types of pilot valves. It will be evident also that but one form of valve control mechanism need be made up 85 and that the single mechanism can be used without change either on high or low pressure cylinders.

While I have in this application specifically described and shown one form which my invention may assume in practice, it will 90 be understood that this form is shown for purposes of illustration and that the invention may be modified and embodied in various other forms without departing from 95 its spirit or the scope of the appended claims.

What I claim as new and desire to secure by Letters Patent is:

1. Unloading means for multistage compressors comprising means for opening the inlet valves of the cylinders of each stage including fluid pressure controlled pistons subjected continuously on one side to the pressure at the intake side of the cylinder with whose inlet valves it cooperates, and on the other side intermittently and in accordance with discharge pressure variations to fluid pressure at higher pressure, said pistons presenting substantially different areas to such intake and higher pressures, the areas at the opposite sides of one of said pistons being such that the force opposing movement thereof during normal compressor running exceeds the force tending to move it resulting from the action thereon of said higher pressure.

2. Means for unloading a compressor by opening the inlet valves thereof comprising a differential cylinder, a differential piston reciprocable therein, means for subjecting one side of said piston continuously to the pressure in the intake chamber of the cylinder with which it is used, and means for intermittently subjecting the other side thereof to compressor discharge pressure, the ratio of the area of the side subject to the pressure in the intake chamber to the area subjected to compressor discharge pressure

- being greater than the ratio of compressor discharge pressure to the pressure in said intake chamber during normal loaded running. 65
5. 3. Means for actuating the inlet valves of a compressor comprising coaxially arranged cylinders in alignment with said valves, oppositely acting pistons in said cylinders, means for subjecting one of said pistons to compressor discharge pressure in excess of a predetermined desired maximum to open said inlet valves, and means for subjecting the other of said pistons to the pressure in the intake chambers of the cylinder whose 70 valve it controls, the product of the area of said first mentioned piston multiplied by compressor discharge pressure being less than the product of the area of said second mentioned piston multiplied by the pressure in the intake chamber of the cylinder whose valve it controls at a time when the compressor is running normally loaded. 75
10. 4. Means for unloading both cylinders of a compound compressor comprising identical means for opening the inlet valves of each of said cylinders, each of said means being subjected to the same pressure to cause opening of said valves, and to the pressures in the intakes of their respective cylinders 80 to oppose opening, said means presenting different areas to said opening and opposing pressures. 85
15. 5. Means for opening the inlet valves of a compressor to unload the latter including a cylinder containing member having aligned bores of different diameters and disposed in alignment with said inlet valves, a multiple piston having portions fitting each of said bores, means for subjecting the smaller of 90 said pistons to receiver pressure to open said valves, and means for connecting the opposite surface of the larger of said pistons to pressure in the intake of its associated compressor cylinder, said means being identical 95 for the several cylinders of multistage compressors and operating to delay the unloading of succeeding cylinders after the unloading of the low pressure stage. 100
20. 6. Unloading means for multistage compressors including identical servo-motors for each cylinder thereof, and means for supplying operating medium to each of said motors to cause the same to unload their respective cylinders, said motors automatically causing the low pressure cylinder to unload first. 110
25. 7. Means for unloading a compressor by opening the inlet valves thereof comprising a cylinder, a piston reciprocable therein, means for intermittently subjecting one side of said piston to a pressure adapted to move the same in a direction to effect compressor unloading, and means for opposing the unloading of the compressor by movement of 115
30. said piston exercising a force greater than the force produced by the action of pressure on said piston as mentioned when said compressor is running loaded, but diminishing to less than said last mentioned force with reduction in pressure at the inlet side of said cylinder. 120
35. 8. Means for unloading a compressor by opening the inlet valves thereof comprising chamber forming means and a movable member therein, means for subjecting a relatively large area at one side of said movable member to the pressure in the intake chamber of the cylinder with which it is used, and means for intermittently subjecting a smaller area at the other side of said member to compressor discharge pressure. 125
40. 9. Means for unloading both cylinders of a compound compressor comprising identical differential pistons for opening the valves of each of the cylinders, each of said pistons being subjected to the same pressure to cause opening of the valves and during the loaded running of the compressor to unequal pressures. 130
45. 10. Means for unloading both cylinders of a compound compressor comprising means associated with each cylinder and operative on actuation to effect unloading thereof, means for actuating said unloading means comprising members adapted to be moved by receiver pressure to effect such actuation and to which receiver pressure is simultaneously admissible when unloading is to occur, and means associated with said members for initially unequally opposing their movements to cause them to become effective at different times. 135
50. 11. Means for unloading both cylinders of a compound compressor comprising means associated with each cylinder and operative on actuation to effect unloading thereof, means for actuating said unloading means comprising members adapted to be moved by receiver pressure to effect such actuation and to which receiver pressure is simultaneously admissible when unloading is to occur, and fluid pressure operated means associated with said members for initially unequally opposing their movements to cause them to become effective at substantially different times. 140
55. 12. Unloading means for multistage compressors comprising means for opening the inlet valves of the cylinders of each stage including identical fluid pressure controlled differential pistons subjected continuously on one side to the pressure at the intake side of the cylinder with whose inlet valves it cooperates, and on the other side intermittently and in accordance with discharge pressure variations to fluid pressure at higher pressure. 145
60. 13. Unloading means for multistage com-

pressors comprising means for opening the inlet valves of the cylinders of each stage including fluid pressure controlled pistons having unequal oppositely acting areas subjected continuously on one side to the pressure at the intake side of the cylinder with whose inlet valves it cooperates, and on the

other side intermittently and in accordance with discharge pressure variations to fluid pressure at higher pressure, said last mentioned side being the smaller. ¹⁰

In testimony whereof I affix my signature.

LOUIS A. MAXSON.
